UNITED STATES PATENT OFFICE.

HARRY L. DAVIS, OF SARATOGA SPRINGS, NEW YORK.

AUTOMATIC WATER-FEED FOR POULTRY.

1,107,268.

Specification of Letters Patent. Patented Aug. 18, 1914.

Application filed August 27, 1913. Serial No. 786,891.

To all whom it may concern:

Be it known that I, HARRY L. DAVIS, a citizen of the United States, residing at Saratoga Springs, in the county of Saratoga and 5 State of New York, have invented certain new and useful Improvements in Automatic Water-Feed for Poultry, of which the following is a specification.

My invention relates to apparatus for 10 automatically regulating the supply of water from a holding receptacle, to a drinking receptacle, designed to be used by poultry.

An important object of my invention is to provide apparatus of the above mentioned 15 character, which is so constructed that a large quantity of water may be held in a tank or barrel, and a small quantity of the same supplied to the poultry drinking receptacle or pan, in an automatic manner, as 20 the water level therein is lowered by the water being drunk by the poultry.

A further object of the invention is to provide apparatus of the above mentioned character, which is so constructed that the 25 same cannot be operated by the poultry except by the same drinking the water which results in a lowering of the level thereof.

A further object of the invention is to provide apparatus of the above mentioned character which may be adjusted so that different 30 depths of water may be constantly maintained in the drinking receptacle or pan.

Other objects and advantages of this invention will be apparent during the course 35 of the following description.

In the accompanying drawing forming a part of this specification, the figure is a side elevation of the complete apparatus, parts thereof being shown in central longitudinal 40 section, for the sake of illustration.

In the drawings, wherein is illustrated a preferred embodiment of my invention, the numeral 1 designates a water holding or supply receptacle, which may be either a tank or 45 barrel, the same being preferably vertically arranged and supported by any suitable means. Connected with the lower end of the preferably vertically arranged water holding receptacle 1 is a preferably horizontal 50 feed pipe 2, having screw-threaded connection at its free end with a T-coupling 3. This T-coupling, at its upper end, has screw-threaded connection with a preferably vertically arranged pipe 4, receiving a valve 55 rod or link 5 therein.

The numeral 6 designates a relatively large

and heavy valve, formed of iron or the like, having a cylindrical body portion 7 and a tapered or conical upper portion 8, decreasing in diameter upwardly. Connected with 60 the upper end of the conical portion 8 is a link 9 receiving a link 10, whereby the valve 6 has a free pivotal connection with the rod 5. The valve 6 has a conical end 11, decreasing in diameter downwardly. The conical end 11 is adapted to enter a tubular-valve-seat 12 having screw-threaded engagement with the lower end of the T-coupling 3, as shown. The upper end of the tapered end 11 is sufficiently large to fit snugly within 65 the bore of the tubular-valve-seat 12. The tubular-valve-seat 12 has its upper end tapered to provide an annular knife edge 13, which engages the lower end of the cylindrical portion 7 of the valve 6, when the valve 70 is seated. The function of having the tubular-valve-seat provided with the knife edge 13 is to provide means for preventing the accumulation of sediment or deposits upon the lower end of the valve 6, the tapered end 11 75 serving to remove deposits from the inner wall of the tapered knife edge, by slidable engagement therewith.

Connected with the upper end of the vertical pipe 4 is a bracket 14, to which is pivoted 80 a vertically swinging lever 15, having one end thereof pivotally connected with the upper end of the valve rod 5, as shown at 16. Pivotedly connected with the opposite end of the lever 15, as shown at 17, is 85 an operating rod 18, the same being provided with a turn buckle 19, whereby its length may be increased or decreased. Connected with the lower end of the T-coupling 3 and extending laterally therefrom is a 90 horizontal arm 20, apertured for receiving the reciprocating operating rod 18. At its lower end the rod 18 has pivotal connection, as shown at 21, with an arm 22, which is attached to one end of a vertically swinging 95 float 23. Connected with the opposite end of the float 23 is an apertured bracket 24, receiving the horizontal arm of an L-shaped supporting rod 25, to be pivotally connected therewith. The vertical arm of 100 the L-shaped supporting rod 25 extends through an opening 26 in the arm 20, and is screw-threaded for receiving clamping nuts 27, disposed upon the upper and lower sides of the arm 20. The vertical arm of 105 the supporting rod 25 does not have screw-threaded engagement with the wall of the 110

opening 26, and the same is raised and lowered by proper manipulation of the clamping nuts 27. It is thus seen that by raising and lowering the supporting rod 25 and adjusting the length of the connecting rod 18, the depth of the water level in the pan or drinking receptacle 28, receiving the float 23 therein, may be permanently regulated. Attention is called to the fact that the float 23 is advantageously located directly beneath the coupling 3 and pipe 2, the same being thus protected, whereby the apparatus cannot be operated by the poultry except by them drinking the water.

15 In the operation of the apparatus, when the water level in the drinking pan or receptacle 28 falls below a predetermined depth, the float 23 descends, drawing operating rod 18 downwardly, which in turn 20 swings lever 15 to elevate valve 6. When the valve 6 is elevated or unseated, the water passes from the holding receptacle 1 through pipe 2 and discharges into the pan 28, such discharge continuing until the desired water level is restored, at which time 25 the valve 6 is automatically returned to its closed or seated position, as is obvious. A particular advantage is gained in having the valve 6 pivotally connected with the rod 30 5, to wit, the fact that said valve is free to partake of independent lateral movements, whereby the tapered end 11 thereof can freely slidably engage the inner wall of the tubular valve seat, for maintaining the 35 knife edge and valve clean.

It is to be understood that the form of my invention herewith shown and described is to be taken as a preferred example of the same, and that various changes in the 40 shape, size and arrangement of parts may be resorted to without departing from the spirit of the invention or the scope of the subjoined claims.

Having described my invention, I 45 claim:—

1. In apparatus of the character described, the combination with a holding receptacle, of an upstanding valve casing connected therewith, a tubular valve seat connected with the lower end of the valve casing and exteriorly beveled to provide a knife edge, a conical valve arranged above the knife edge and adapted to be moved

downwardly into the same, a rod pivotally connected with the conical valve and 55 adapted to swing relative to the knife edge, and float controlled means connected with the rod.

2. The combination with a water holding receptacle, of a laterally extending pipe 60 connected therewith, an upstanding valve casing connected with the discharge end of the pipe and provided near its lower end with a valve seat, a valve movably mounted within the upstanding valve casing to engage and disengage the valve seat, a lever pivotally connected with the upper end of the upstanding valve casing to swing in a substantially vertical plane, a rod connecting the lever and valve, an approximately 65 L-shaped supporting rod connected with the lower end of the valve casing with its lower arm extending beneath the laterally extending pipe, a float pivotally connected with the free end of the lower arm of the L-shaped supporting rod, a rod connecting the opposite end of the float and the pivoted lever, and a receptacle arranged below the float.

3. In apparatus of the character described, the combination with an upstanding holding receptacle, of a pipe connected with the lower portion thereof, a T-coupling connected with the pipe, a valve seat connected with the lower end of the T-coupling, a vertical pipe connected with the upper end of the T-coupling, a valve movably mounted within the T-coupling, a lever pivotally connected with the upper end of the vertical pipe to swing in a substantially vertical plane, a rod connecting the lever and valve, an L-shaped supporting rod vertically adjustably connected with the T-coupling with its horizontal arm extending beneath the T-coupling, a float having 90 one end pivotally connected with the horizontal arm of the supporting rod, and a rod pivotally connected with the opposite end of the float and the vertically swinging lever.

In testimony whereof I affix my signature in presence of two witnesses.

HARRY L. DAVIS.
